UNITED STATES PATENT OFFICE.

JOHN ALLEN AND EDWARD PICK, OF BROOKLYN, NEW YORK.

IMPROVEMENT IN OVENS.

Specification forming part of Letters Patent No. 35,661, dated June 24, 1862.

To all whom it may concern:

Be it known that we, JOHN ALLEN and EDWARD PICK, of the city of Brooklyn, in the county of Kings and State of New York, have invented certain new and useful Improvements in Bake-Ovens; and we do hereby declare that the following is a full and correct description thereof, reference being had to the annexed drawings, making a part of this specification, and to the letters of reference thereon.

Our invention consists of several improvements in the class of ovens known generally as "reel-ovens," and described in books and in Letters Patent of the United States to Hosea Ball, September 23, 1856, Duncan McKenzie, May 1, 1860, and Iverson W. Knapp, February 18, 1862.

First. We dispense with the draft-opening in the top of the baking-chamber, and use a draft and steam-flue opening from the mouth of the oven. By this change in the location of the draft-flue we keep a sufficient amount of steam at all times in the oven while baking, and at the same time get a draft, and also protect the workman from the steam when charging and discharging the bread. We are aware that in the old brick ovens in which the bread is baked on the bottom of the oven, and the oven-mouth is on a level with the bottom of the oven, steam and draft flues opening from the mouth have been used; but such flues have not been used, to our knowledge, in reel-ovens, which are very different in construction and operation from the ordinary bake-oven.

Second. Our invention further consists in combining with the baking-chamber two outlets or draft-flues opening from opposite sides of the oven, at an elevation above the floor of the oven and below the mouth of the oven, said flues being connected with the chimney by flues passing upward through the exterior walls of the oven, and not downward below the floor of the oven, as in McKenzie's oven. By this arrangement we are enabled to get a draft below the oven-mouth and yet have sufficient elevation of outlet above the fire to secure active combustion, and, besides, we do not take up any part of the bottom or floor of the oven with openings and flues used only for draft, and therefore comparatively cold.

Third. Our invention further consists in a double series of horizontal flues, in combination with the furnace and floor of a reel-oven,

for the purpose of more thoroughly heating the bottom part of the oven through the floor by radiated heat.

But to describe our invention more particularly, we will refer to the annexed drawings, of which—

Figure 1 is a front elevation of the oven; Fig. 2, a transverse section through dotted lines *x x*, Fig. 3; Fig. 3, a cross-section through the middle of the oven; Fig. 4, a horizontal section showing outlets and steam-flue; Fig. 5, a horizontal section through dotted lines *y y*, Fig. 2, showing plan of fire-box and heating-flues under the bottom of the oven.

Letter *a* represents the baking-chamber of a reel-oven of suitable size and shape to contain and permit of the operation of gravitating bread-pans *b*, suspended from the radial arms *c* of the horizontal shaft *d*. This apparatus is commonly called a "reel," and is rotated by hand or machinery from the outside of the oven, one end of the shaft projecting through the side of the oven for that purpose.

Letter *e* represents the mouth of the oven; *e'*, a sliding door for the same, counterbalanced by the weight *e²*, connected to the door by a chain, *e³*, passing over pulleys *e⁴ e⁵*.

Letter *f* is a steam and draft flue opening from the roof of the mouth of the oven, controlled by a suitable damper, *f'*, and connected with the chimney by running into the draft-flue *g*, which opens into the oven at *h* and passes horizontally within the front wall to near the side of the oven, and thence up to the top and back over the top, and then by an inclined flue to the chimney.

Letter *i* represents a rear draft-flue opening into the oven at *j*, and passing straight up through the back wall of the oven to the chimney. The front and rear draft-flues may unite in one chimney-flue, as shown in the drawings, or be connected with separate and independent chimney-flues. The front and rear draft-flues are governed, respectively, by suitable dampers, *g'* and *i'*.

Letter *k* represents the floor of our oven, which is flat, being merely a covering of refractory fire-clay blocks and tiles over the furnace and horizontal flues.

Letter *l* is the fire-box provided with suitable doors, grate, ash-pit, &c.; *m*, a chamber behind the furnace, without any back outlet. *n n* are horizontal flues on each side of the

furnace, supplied with products of combustion from the fire-box through the small passages *o* at the side of the fire-box above the pipe. The flues *n n* discharge through the passage-way *p p* into the horizontal side flues, *q q*, (one at each side of the oven,) which, besides being heating-flues for the bottom, like the adjoining horizontal flues, perform the office of distributing flues or chambers, the heat and products of combustion being conducted from them to the inside of the baking-chamber by the short flues or passages *r*.

We prefer to arrange the passages *r* near the ends of the flues *q q*, as shown in the drawings, and to have the passages *p p* open from the middle of the adjoining horizontal flues, opposite the dead-wall of the flues *q q*, as shown. The passages *r* may be graduated in respect to their size, those farthest from the passages *p p* being made largest, so as to draw equally.

From the above description it will be evident to the practical baker that in consequence of the interposition of the horizontal flues between the fire-box and the baking-chamber, a larger proportion of the fuel consumed is appropriated to produce an effective bottom heat, or a heat striking upward against the under side of the bread-pans from the bottom of the oven, than by former constructions, which are defective in respect to bottom heat, owing to the heat being conducted from the fire-box so

directly and immediately into the baking-chamber or between the outer and inner side walls of the same that the temperature is greatest in the top part of the oven, and consequently the heat more active upon the bread from above than from below.

Our said improvements are peculiarly useful in baking hard bread—such as ship-bread or army-bread—which require a strong heat on the bottom side.

We claim as our invention and improvements in mechanical bake-ovens known as "reel-ovens"—

1. The draft and steam flue opening from the mouth of the oven when combined with a baking-chamber suitable for and containing the reel apparatus and bake-pans, substantially as described.

2. The side draft-flues, in combination with the baking-chamber of a reel-oven when opening below the mouth of the oven and above the floor, substantially as described.

3. The double series of horizontal heating-flues, in combination with the furnace and floor of a reel-oven, constructed and arranged substantially as described.

JOHN ALLEN.
EDWARD PICK.
